UNITED STATES PATENT OFFICE.

JOHN A. HULIT, OF CHICAGO, ILLINOIS.

TELEGRAPH SENDING INSTRUMENT.

Application filed February 15, 1922. Serial No. 536,612.

To all whom it may concern:

Be it known that I, JOHN A. HULIT, a citizen of the United States, and a resident of Chicago, Cook County, Illinois, have invented a certain new and useful Improvement in Telegraph Sending Instruments, of which the following is a specification.

This invention relates to telegraph apparatus for transmitting or sending messages.

Generally stated, the object of the invention is to provide novel and improved means whereby a succession of dots may be transmitted without the necessity of more than one movement of the hand of the operator, thus obviating the necessity of a separate movement for each dot, and whereby each dash is produced by a movement of the hand of the operator, in the ordinary way, all by one and the same key, thus reducing the amount of labor and effort necessary on the part of the operator to transmit messages over a considerable period of time, and reducing the strain imposed on the operator, as will hereinafter more fully appear.

It is also an object to provide certain details and features of construction and combinations tending to increase the general efficiency and desirability of a telegraph sending instrument having means of this particular character for transmitting a plurality of dots by one and the same movement of the same sending key by which the operator transmits the dashes by a separate movement of the key for each dash.

To this and other useful ends the invention consists in matters hereinafter set forth and claimed and shown in the accompanying drawings in which—

Figure 1 is a plan of a telegraph sending instrument having dot and dash transmitting means embodying the principles of the invention.

Figure 2 is a side elevation of said instrument.

Figure 3 is a similar view showing the other side of said instrument.

Figure 4 is a transverse section on line 4—4 in Figure 1.

Figure 5 is a similar section on line 5—5 in Figure 1.

Figure 6 is a similar section on line 6—6 in Figure 1.

Figure 7 is a horizontal section on line 7—7 in Figure 3.

Figure 8 is a detail view showing a por-

tion of the bottom of the base upon which the various devices constituting said instrument are mounted for operation.

As thus illustrated the invention comprises a base 1 upon which are mounted the transversely arranged and oppositely disposed plates 2 and 3 which are rigidly connected together at their upper ends by horizontal plates 4, thus forming a rectangular frame on said base. An upright pivot 5 supports the horizontally movable key bar or lever 6 which is provided at its outer end with the handle 7 of any suitable character. This bar or lever 6 swings in the guide formed by the notch 8 in the plate 2, this horizontal swinging movement being limited on one side by the adjustable screw stop 9 and at the other side by the stationary stop or contact 10 on the block 11, said bar or lever 6 having an adjustable screw 12 for engaging the contact 10, thereby to close the circuit for the dashes. Another bar or lever 13 is mounted on the vertical pivot 5, above the bar 6, and a stationary contact screw 14 mounted in a stationary block 15 on the frame engages the bar 13 to limit its motion in one direction. The bar 13 is provided with a depending bracket 16 to which is attached the spring 17 which is connected at its other end to the adjusting screw 18 by which the tension of this spring is regulated. It will be seen that the spring 17 draws the bracket 16 against the key-bar 6, and thereby normally draws the latter toward the screw 9 previously mentioned, and, of course, this spring 17 normally holds the bar 13 against the screw 14 previously mentioned, whereby the previously mentioned contacts 10 and 12 are normally open. The bar 13 is provided with a bracket 19 upon which is mounted an adjusting screw 20, and this screw is connected by the spring 21 with the bar 6, whereby this spring is compressed when the lever 6 is swung over against the screw 9, this being the movement of the key which produces the dots as will more fully appear. Thus the bar 6 is normally out of contact with the screw 9, and is also out of contact with the stationary electrical contact 10, being yieldingly maintained in this position by the two springs 17 and 21 connected and arranged in the manner shown and described. As stated, to produce the dashes the operator moves the key lever 6 to the left to bring the screw 12 into engagement with the con-

tact 10, and then releases the lever to normal position, thus manually producing the dashes in a manner that will be readily understood.

- 5 The means for automatically producing a succession of dots, by merely one movement of the key lever 6, are as follows: A longitudinal shaft 22 is suitably mounted in bearings on the frame and is provided with 70
10 a gear wheel 23 which engages the pinion 24 on the shaft 25 which is connected by worm gearing 26 with electric motor 27 mounted on the base. The gear wheel 28 is loose on said shaft 22 and is subject to 75
15 the pressure of a friction clutch 29 having a coil spring 30 on said shaft, whereby the gear wheel 28 may remain stationary while the gear wheel 23 is driven constantly by said motor. The gear wheel 28 is thus normally held stationary by its engagement with the pinion 31 on the upper shaft 32, which is supported in suitable bearings on the frame. A ratchet-wheel 33 is mounted on the outer end of this shaft 32 and is held 80
20 normally against rotation by a dog 34 held in engagement therewith by the tension of the spring 35 connected to the lower end of said dog, the latter being pivoted at 36 to swing toward and away from said ratchet-wheel. A plate 37 on the key lever 6 normally engages the dog 34, whereby this dog is released from said ratchet-wheel when said key lever 6 is swung laterally to the right. A lever 38 engages the toothed wheel 85
25 39 on the shaft 32, being pivoted at 40 to swing about a horizontal axis. The lower end portion of the lever 38 serves as a contact to engage the stationary contact 41, the two contacts being normally open. A 90
30 spring 42 is connected to the lever 38, below the pivotal point 40, so that this lever is vibrated when the shaft 32 is rotated, and at such time the flexibility of the lower portion of the lever 38 is sufficient to enable it 95
35 to engage the contact 41 when retracted by the spring 42, thus producing the make and break action in the circuit to produce the dots. Thus, when the lever 6 is moved to the right, the wheel 33 is released by the dog 34, and the shaft 32 is rotated to rapidly open and close the contacts formed by the lower end of the lever and the screw 41, and a succession of dots will be sent over the line circuit as long as the key lever is 100
40 maintained in this position. It will be understood, of course, that the friction clutch 29 drives the shaft 32 as soon as the latter is released by the disengagement of the dog 34 from the ratchet-wheel 33, thus producing the desired result; but while the dog 34 is in engagement with the ratchet-wheel 33, the shaft 32 cannot rotate, and the gear wheel 28 is held stationary. 105
45

It will be understood that in practice the contacts 10 and 12 for the dashes are suit-

ably connected in the line circuit, and are normally open, while the contacts formed by the lower end of the lever 38 and the screw 41 are connected in the line circuit in parallel or multiple with the contacts 10 and 12, whereby the line circuit can be closed at either one of the two points thus connected in multiple, and whereby the operator can close either point at will. When the key lever 6 is swung to the left, from its normal position, the contacts 10 and 12 are closed and a dash is transmitted. On the other hand, when the key lever is swung to the right the contacts formed by the lower end of the lever 38 and the screw 41 are rapidly opened and closed, automatically, in the manner described, by the power furnished by the electric motor, and the operator may send any number of dots in succession with but one movement of the hand. Of course, the operator becomes skilled in the use of the instrument and learns how to control the mechanism to send as many dots as are necessary at any one time, in accordance with the code being used. 90
50 In other words, it is not necessary for the operator to employ a separate movement of the hand for each dot, for any number of dots may be sent in succession by one movement of the hand, thus reducing the amount of effort and labor necessary on the part of the operator to transmit messages, relieving the strain on the operator incident to long periods of service or duty at the telegraph key. Of course, in the transmission of one 95
55 or two messages, the ordinary method does not tire the operator, but for a day's work, or for several hours' continuous duty at the key, a separate movement of the hand for each dot rapidly counts up and in the aggregate represents considerable effort and strain to which the operator is subject when the messages are sent in the ordinary manner. However, when only one movement of the hand is necessary for any desired number of dots, it is obvious that the effort and labor necessary on the part of the operator is greatly reduced. It will be understood, of course, that the circuit wires can be arranged in any suitable manner, in order to 100
60 include the make and break contacts in the line circuit, so that the instrument will be operative to transmit telegraphic messages by use of the key lever in the manner described. The motor runs continuously, of course, but this power is only utilized for the sending of the dots, the dashes being transmitted in the ordinary manner and without any assistance from said motor or other source of power. Obviously, of course, the motor can be regulated or controlled to ensure the necessary or desired speed of operation thereof. 105
65

From the foregoing it will be seen that the invention involves a constantly operat-

70

ing motor, and by this is meant any form of motor, of course, for while an electric motor is shown and described it will be understood that any source of power can be employed 5 without departing from the spirit of the invention.

The novel means provided for automatically transmitting a succession of electrical impulses, over a line circuit, are shown as 10 10 constituting the means for transmitting dots in a telegraph system, but it will be understood that said novel means can be employed for transmitting electrical impulses for any suitable or desired purpose.

15 Thus the single make and break device 38 and 41 is adapted to send or transmit different combinations of electrical impulses, or to send different combinations of dots, and hence this is not a make and break 20 device which has one predetermined mode of operation to always transmit or send a predetermined number of dots or impulses. To the contrary, this make and break device is controllable by the key to transmit different 25 combinations of impulses, and hence the make and break device in question is not individual or allotted to any particular letter of the alphabet, but to the contrary is necessary for the transmission of any letter 30 of the alphabet containing dots. The key does not operate the make and break device, but merely exercises control thereover to determine the different combinations of impulses to be transmitted.

35 What I claim as my invention is—

1. The combination of a make and break device to transmit dots, a constantly operating motor, power transmitting means to transmit power from said motor to said 40 device, and a key to manually control said power transmitting means and whereby to start and stop the operation of the device at will, thereby to transmit different combinations of dots, without stopping the operation of said motor, so that all of the dots 45 of any message are transmitted by the operation of said device by said motor under the control of said key, in combination with a second make and break device controlled 50 by said key to transmit the dashes, said key being operative by a single movement in one direction to transmit a succession of dots, and being operated by movement in the opposite direction to transmit a dash.

55 2. A structure as specified in claim 1, said power transmitting means comprising a normally closed friction clutch one member of which is held normally against rotation by the normal position of said key.

60 3. A structure as specified in claim 1, comprising a ratchet dog for normally preventing operation of said device, and means on said key to disengage said ratchet dog to permit operation of said device.

65 4. A structure as specified in claim 1, said

make and break device comprising a stationary contact and a vibratory lever for engaging said contact, rotary means for engaging and vibrating said lever and a spring applied to said lever to ensure the necessary 70 vibratory movement thereof.

5. A structure as specified in claim 1, said power transmitting means comprising two gear wheels arranged close together with a friction drive connection from one to the other, a pinion for driving one gear wheel, and a pinion driven by the other wheel, said last mentioned pinion being held normally against rotation by the normal position of said key, whereby one gear wheel rotates 80 continuously while the other one rotates intermittently under control of said key.

6. The combination of a make and break device to transmit dots, a constantly operating motor, power transmitting means to 85 transmit power from said motor to said device, and a key to manually control said power transmitting means and whereby to start and stop the operation of the device at will, thereby to transmit different combinations of dots, without stopping the operation of said motor, so that all of the dots 90 of any message are transmitted by the operation of said device by said motor under the control of said key, said key being movable horizontally in one direction, and having means whereby such movement controls the power transmitting means to start the operation of said device, in combination with a second make and break device controlled 95 by movement of said key in the opposite direction to transmit dashes, springs to hold said key in normal position, so that both of said make and break devices are normally open, and a vertically disposed pivot for said key, the two make and break devices being adapted for connection in multiple to a line circuit.

7. The combination of a make and break device to transmit dots, a constantly operating motor, power transmitting means to transmit power from said motor to said device, and a key to manually control said power transmitting means and whereby to start and stop the operation of the device 110 at will, thereby to transmit different combinations of dots, without stopping the operation of said motor, so that all of the dots of any message are transmitted by the operation of said device by said motor under the control of said key, in combination with a second make and break device controllable by said key to transmit dashes, the two make and break devices being connected in multiple to a line circuit.

8. In a telegraph sending instrument, a make and break device for transmitting any desired number of dots in succession, so that all of the dots for any message are transmitted by the operation of said device, a 130

- ratchet dog for normally preventing operation of said device, operating means to actuate said device when released by disengagement of said ratchet dog, and a control key having means for disengaging said ratchet dog to start the operation of said device by said operating means, in combination with a second make and break device controlled by said key to transmit dashes, and springs for holding said key in normal position, so that both of said devices are normally open, said devices being adapted for connection in multiple to a line circuit.
15. 9. A structure as specified in claim 8, said means for operating said device comprising a toothed wheel held normally against rotation by said ratchet dog, and a vibratory lever engaging said toothed wheel.
10. A structure as specified in claim 8, said means for operating said device comprising a normally closed friction clutch one member of which is constantly rotating and the other member of which is held normally against rotation by said ratchet dog.
11. The combination of a make and break device to transmit dots, a constantly operating motor, power transmitting means to transmit power from said motor to said device, and a key to manually control said power transmitting means whereby to start and stop the operation of the device at will, without stopping the operation of said motor, in combination with a second make and break device controllable by a said key to transmit the dashes, said key being operative by a single movement in one direction

to transmit a succession of dots, and being operated by movement in the opposite direction to transmit a dash.

12. The combination of a make and break device to transmit dots, a constantly operating motor, power transmitting means to transmit power from said motor to said device, and a key to manually control said power transmitting means and whereby to start and stop the operation of the device at will, without stopping the operation of said motor, said key being movable horizontally in one direction, and having means whereby such movement controls the power transmitting means to start the operation of said device, in combination with a second make and break device controlled by movement of said key in the opposite direction to transmit dashes, springs to hold said key in normal position, so that both of said make and break devices are normally open, and a vertically disposed pivot for said key, the two make and break devices being adapted for connection in multiple to a line circuit.

13. The combination of a make and break device to transmit dots, a constantly operating motor, power transmitting means to transmit power from said motor to said device, and a key to manually control said power transmitting means whereby to start and stop the operation of the device at will, without stopping the operation of said motor, in combination with a second make and break device controllable by said key to transmit dashes, the two make and break devices being connected in multiple to a line circuit.

JOHN A. HULIT.
